UNITED STATES PATENT OFFICE.

BENEDICT T. GIBBS, JR., OF CHICAGO HEIGHTS, ILLINOIS, ASSIGNOR TO MORDEN FROG & CROSSING WORKS, OF CHICAGO, ILLINOIS, A CORPORATION OF ILLINOIS.

RAILWAY-SWITCH STAND.

Application filed December 15, 1922. Serial No. 607,082.

To all whom it may concern:

Be it known that I, BENEDICT T. GIBBS, Jr., a citizen of the United States, residing at Chicago Heights, in the county of Cook and State of Illinois, have invented a certain new and useful Improvement in Railway-Switch Stands, of which the following is a specification.

This invention relates to railway switch stands, specifically those of the type conventionally installed across two ties at the side of a switch to operate the switch point.

For a variety of reasons, well understood in the art unnecessary to enumerate here, it is desirable in such a stand to provide a certain amount of intentional lost motion, as distinguished from objectionable looseness found in improperly built or seriously deteriorated mechanisms.

The object of this invention is to provide a conventional form of switch stand with such an intentional lost motion device, which is so located that it is easily built and readily accessible when the stand is in use, for repair or replacement.

The invention consists in mechanism for attaining the foregoing and other objects and in many features and details of construction which will be hereafter more fully set forth in the specification and claims.

Referring to the drawings in which like numerals designate the same parts throughout the several views:

Figure 1 is a sectional plan view, taken on the line 1—1 of Figure 2, illustrating this invention in its preferred form.

Figure 2 is a side elevation largely in section, taken on the line 2—2 of Figure 1.

Figure 3 is a similar view at right angles to that of Figure 2, taken on a line 3—3 of Figure 1.

Figure 4 is a perspective view of the essential detail parts entering into this invention, removed from the switch stand proper.

Figure 5 is a side view and Figure 6 a plan view of an alternative form of construction of the part shown in Figure 4.

Figure 7 is a bottom view of the crank mechanism of Fig. 2.

The switch stand, case of conventional form to which this invention is applied, including a base portion 10 and a cover 12, secured in place by any suitable means, as, for instance, bolts 14, is shown applied to

two railroad ties 16 and 18 by any suitable means, as, for instance, the spikes 20, in such a position that the conventional switch rod 22, operated by the device, can extend away between the ties to the switch point, 60 not shown, to be controlled.

Journalled in the switch stand case in the obvious manner is a shaft 24, conventional as to all except its lower portion, the same carrying the segmental gear 26 meshing with another gear 28 on a horizontal shaft 30, extending outside the case, and there carrying a conventional operating lever 32 equipped at its end with the usual weight 34, adapted to be rocked in a vertical plane between the position shown in Fig. 1 and a corresponding position 180° therefrom, in which it rests upon member 36 on tie 16 as distinguished from member 38 on tie 18. The upper end of shaft 24 is conventionally provided with the target or lantern holding non-circular end 40.

The rotatable shaft 24 is in the preferred construction provided with the non-circular lower end 42, adapted to receive the cylindrical hub 44 of a non-circular nut 46, the same being detachably secured in place by any suitable means, as, for instance, the pin and cotter construction 48 of Figure 3.

Interposed between the bottom portion 10 of the stand case and the non-circular parts 46, heretofore referred to, and journalled on the hub 44, is the cylindrical hub 49 of two oppositely disposed crank arms 50 and 52, each selectively attachable to the switch rod 22 by any suitable means, as, for instance, the bolt 54. The inner connecting portion 56 of these two crank arms 52 and 54 is provided with an elongated recess 58 of substantially the same contour but slightly larger than the non-circular nut portions 46, with the result that when the parts are assembled as shown in the drawings with the nut members 46 in the recess 58, there is just the right amount of play or lost motion 100 between members 46 and 56.

The construction described has the distinct advantage that, by removing cotter pin 48, the nut member 46 may be dropped out of the lever mechanism 50—52 and replaced by a new one of the same size or a different size, as may be required for the switch constructing operation, without its being necessary to in any way disturb the rest of the switch stand. Furthermore, these adjust- 110

able parts are so located that they are in large measure protected by the body of the stand from access by rain or snow and yet the stand, itself, does not have to be opened in order to reach them for replacement or repair, as described.

In the alternative construction of Figures 5 and 6, the lower end of vertical shaft 24 is provided with an integral cam or nut 60 of approximately the shape of member 46, while the lever arm mechanism 62, corresponding to device 50—52, is provided with an open-topped recess 64 loosely enclosing member 60 with just sufficient clearance to give the desired amount of lost motion in the entire mechanism. In this construction, the lever device 62 is detachably secured to the bottom of shaft 24 below cam 46 through the agency of an elongated slot 66 and pin 68 connection of conventional form, so shaped and adjusted as to allow the necessary amount of play between the members 60 and 62 to give the desired lost motion effect.

In this alternative construction, most of the advantages of the preferred construction are present and, in addition, there is only one loose part, viz: the crank mechanism 62, which is separated from the switch stand when the pin 68 is removed, instead of two parts as in the preferred construction. This reduces the danger of accidental loss of parts. In the alternative construction of Figure 5, the hub 70 of lower case member 10 is split vertically, at a point not shown, to permit the insertion of shaft 24 to the position shown.

Attention is called to the fact that by completely enclosing the non-circular members in the crank arm and its hub, the height of the stand is kept at a minimum.

Having thus described my invention, what I claim as new and desire to secure by Letters Patent is:

1. In mechanism of the class described, in combination with a shaft, means for rotating it and a switch rod to be operated by the shaft; a crank arm attached to the connecting rod, having a non-circular opening entered by said shaft, and a non-circular member, non-rotatable on the shaft, carried by the shaft, loosely fitting, by a predetermined amount, in said non-circular opening for the purposes set forth.

2. In mechanism of the class described, in combination with a shaft, means for rotating it and a switch rod to be operated by the shaft; a crank arm attached to the connecting rod, having a non-circular opening entered by said shaft, and a non-circular member non-rotatable on the shaft, detachably carried by the shaft loosely fitting, by a predetermined amount, in said non-circular opening, for the purposes set forth.

3. In mechanism of the class described, in

combination with a shaft, means for rotating it and a switch rod to be operated by the shaft; a crank arm attached to the connecting rod, having a non-circular opening entered by said shaft, a journal bearing between the shaft and crank arm, and a non-circular member non-rotatable on the shaft carried by the shaft loosely fitting, by a predetermined amount, in said non-circular opening for the purposes set forth.

4. In mechanism of the class described, in combination with a shaft, means for rotating it and a switch rod to be operated by the shaft; a crank arm attached to the connecting rod, having a non-circular opening entered by said shaft, a journal bearing between the shaft and crank arm, and a non-circular member non-rotatable on the shaft, detachably carried by the shaft loosely fitting, by a predetermined amount, in said non-circular opening, for the purposes set forth.

5. In mechanism of the class described, in combination with a shaft, means for rotating it and a switch rod to be operated by the shaft; a crank arm attached to the connecting rod, having a non-circular opening entered by said shaft, a journal bearing between the shaft and crank arm, and a non-circular member non-rotatable on the shaft, detachably carried by the shaft loosely fitting, by a predetermined amount, in said non-circular opening, the non-rotatable member being at the end of the shaft and assisting in holding the crank arm on the shaft.

6. In mechanism of the class described, a shaft having a non-circular end and a bearing portion adjacent thereto for rotation in a case, a crank arm enclosing the end of the shaft having a non-circular opening freely entered by the non-circular end of the shaft and a non-circular member detachably carried by the non-circular end of the shaft, having a part constituting a journal bearing for the crank arm and having a part fitting loosely by a predetermined amount in the opening in the crank, the entire non-circular member being within the body of the crank, and means detachably securing all the parts in operative position.

7. In mechanism of the class described, in combination with a shaft, means for rotating it and a switch rod to be operated by the shaft; a crank arm attached to the connecting rod, having a non-circular opening entered by said shaft, and a non-circular member, non-rotatable on the shaft, carried by the shaft, completely enclosed in the crank arm, loosely fitting, by a predetermined amount, in said non-circular opening for the purposes set forth.

8. In mechanism of the class described, in combination with a shaft, means for rotating it and a switch rod to be operated by

the shaft; a crank arm attached to the connecting rod, having a non-circular opening entered by said shaft, and a non-circular member non-rotatable on the shaft, having 5 a hub detachably carried by the shaft completely enclosed in and forming a bearing for the crank arm, said non-circular member loosely fitting, by a predetermined amount, in said non-circular opening, for the purposes set forth.

9. In mechanism of the class described, in combination with a shaft, means for rotating it and a switch rod to be operated by the shaft; a crank arm attached to the connecting rod, having a non-circular opening entered by said shaft, a journal bearing between the shaft and crank arm, and a non-circular member non-rotatable on the shaft carried by the shaft loosely fitting, by a predetermined amount, in said non-circular

opening, the mounting for the non-circular member on the shaft constituting said journal bearing, for the purposes set forth.

10. In mechanism of the class described, in combination with a shaft, means for rotating it and a switch rod to be operated by the shaft; a crank arm attached to the connecting rod, having a non-circular opening entered by said shaft, a journal bearing between the shaft and crank arm, and a non-circular member non-rotatable on the shaft, detachably carried by the shaft loosely fitting, by a predetermined amount, in said non-circular opening, the mounting for the non-circular member on the shaft constituting said journal bearing, for the purposes set forth.

In witness whereof, I have hereunto subscribed my name.

BENEDICT T. GIBBS, JR.
